GLOVE RACK

Arnold W. Hillman, Wakeeney, Kans., assignor of
one-fourth to Harold F. Hillman, Wakeeney,
Kans.

Application March 3, 1939, Serial No. 259,641

1 Claim. (Cl. 211—13)

The present invention relates to display racks and has particular reference to a rack of this character designed to display gloves in a convenient arrangement by means of which the 5 gloves may be easily inspected and selected.

More specifically, the invention comprises a rack including a plurality of vertically spaced shelves and in which the shelves are separated into compartments by means of vertically extending rods in order that the gloves may be separated according to sizes and styles, the rods forming the partitions between the compartments serving to enable inspection of the gloves without necessitating removal from the rack.

15 A still further object is to provide a display rack of this character of simple and practical construction, which is strong and durable, which may be easily moved into a desired position, which is neat and attractive in appearance and 20 otherwise well adapted to the purposes for which the same is intended.

Other objects and advantages reside in the details of construction as more fully hereinafter described and claimed, reference being had to 25 the accompanying drawings forming part hereof, wherein like numerals refer to like parts throughout, and in which—

Figure 1 is a front elevational view.

Figure 2 is a vertical sectional view.

30 Figure 3 is a transverse sectional view taken substantially on a line 3—3 of Figure 2, and

Figure 4 is a fragmentary perspective view of one side of the rack showing the arrangement of the rods projecting through the shelves to form 35 the partitions therein.

Referring now to the drawings in detail, wherein for the purpose of illustration I have disclosed a preferred embodiment of the invention, the numeral 5 designates a pair of side members of 40 the rack supported upon swivel rollers 6, the side members at their lower front edges being connected by a horizontal spacing member 7. Each of the side members at the lower rear edge thereof, is formed with an extension 8 of predetermined configuration, as clearly shown in Figure 2 of the drawings, to increase the supporting area at the bottom edge of the side members.

The inner surface of each of the side members 5 is provided with vertically spaced horizontally 45 extending grooves or channels 9 within which are conformably fitted the end portions of vertically

spaced shelves 10. The side members are connected at their upper edges by a top 11 and as more clearly illustrated in Figure 2 of the drawings, the front edge of the side members and the rear edge thereof, above the extension 8 extend 5 parallel and in a rearwardly inclined position, while the shelves 10 extend horizontally.

Each of the shelves including the bottom shelf is provided with vertically aligned openings 12 in which rods 13 are inserted, the lower ends of 10 the rods being retained against removal by a strip 18 suitably secured to the under side of the bottom shelf, the upper ends of the rods being recessed in the top 11. A group of the rods are arranged in parallelism with respect to the side 15 members 5 to provide vertical partitions whereby to form compartments or so-called pigeonholes 14 between each of the shelves, the rear of each compartment being closed by vertically extending spaced rods 15 which are inserted through open- 20 ings adjacent the rear edge of each of the shelves.

Each of the compartments is provided with a label holder 16 secured to the front edge of each of the shelves.

The compartments 14 are adapted to contain 25 gloves or similar articles of apparel for display purposes and the compartment 17 at one end of the shelves is constructed of an increased area to accommodate gloves of the gauntlet type.

It is believed the details of construction will be 30 readily understood from the foregoing without further detailed explanation.

Having thus described the invention, what I claim is:

A display rack comprising a pair of upstanding 35 side members having their vertical edges inclined rearwardly, rollers supporting the members, extensions on the lower rear edges of the members providing an underlying support for the rear of the rack, a top member having recesses therein 40 secured to said side members, apertured shelves secured to and between said side members, inclined rods projecting through the apertured shelves and arranged in spaced rows to provide open-work partitions between the shelves with 45 their top ends engaged in said recesses, said rods including a row extending across the rear of the shelves to provide an open-work back, and means secured to the bottom side of the bottom shelf to support said rods. 50

ARNOLD W. HILLMAN.
